INVENTOR
Victor J. Evans
BY ATTORNEY

UNITED STATES PATENT OFFICE.

MORGAN A. GREENE, OF SALINA, KANSAS.

TROUSERS SUPPORTER.

Application filed April 17, 1922. Serial No. 553,322.

To all whom it may concern:

Be it known that I, MORGAN A. GREENE, a citizen of the United States, residing at Salina, in the county of Saline and State 5 of Kansas, have invented new and useful Improvements in Trousers Supporters, of which the following is a specification.

This invention relates to garment supporters, particularly to devices for supporting trousers, and has for its object the provision of a device of this character designed for engagement with trousers and with suspenders, whereby the suspenders may be worn under the dress shirt, the device being 10 so constructed and arranged as to permit this use while also permitting the lower portion of the shirt to be properly tucked into the top of the trousers in such a way as to provide a neat appearance and to prevent rumpling or wrinkling of the shirt.

An important and more specific object is the provision of a supporter of this character which is so constructed and arranged as to permit dropping down of the trousers 15 when necessary without necessitating the unbuttoning of the trousers or the unbuttoning of the supporter from the suspenders.

An additional object is the provision of a device of this character which will be 20 simple and inexpensive in manufacture, easy to apply and use, highly efficient and durable in service and a general improvement in the art.

With the above and other objects and advantages in view, the invention consists in the details of construction to be hereinafter more fully described and claimed, and illustrated in the accompanying drawings, in which:

Figure 1 is a view looking at the upper portion of a pair of trousers and showing my device in position.

Figure 2 is a vertical sectional view showing the normal position of the device in associating with the trousers and suspenders.

Figure 3 is a similar view showing the device straightened out to permit lowering of the trousers, and

Figure 4 is a detail perspective view of 50 my supporter alone.

Referring more particularly to the drawing, the letter A designates a portion of a pair of trousers equipped with the usual waist band B which is provided on each 55 side with a pair of spaced buttons C upon which are ordinarily engaged suspenders D.

In carrying out my invention I provide a supporter which is interposed between the trousers or rather the waist band thereof and the suspenders. This supporter comprises a body 10 of thin flexible material which yet has a certain degree of thickness whereby it will not fold or bend upon itself accidentally. This body is here shown as being of substantially trapezoidal shape and 60 curved laterally whereby to conform to the hips of the wearer, this body being furthermore provided at its upper corners with extensions 11 upon which are secured by any suitable means flexible tabs 12 provided 65 with buttonholes 13 for engagement upon the buttons C at the waist band of the trousers. Suitably secured at the lower edge of the body 10 is an elongated strip 14 of 70 flexible material which is designed to be 75 looped about a portion of the suspenders D and it is preferable that this strip be provided with a snap fastener 15 with which 80 may be engaged any one of a plurality of mating fastener elements 16 provided throughout the length of the strip. This means provides adjustment so that the 85 suspenders may be regulated to the proper length to effect the most efficient service.

In actual practice the device is used in 85 duplicate, that is to say one body member 10 is disposed inside of the trousers and the tabs 12 are engaged upon the buttons C ordinarily provided at the waist band of the garment. The body member 10 extends 90 downwardly and the flexible strip 14 at the lower edge thereof is brought upwardly and looped through the suspenders and then the snap fastener 15 is engaged with the proper one of the fastener elements 16 co- 95 operating therewith whereby to maintain this proper adjustment. When the device is thus applied it will be apparent that the lower end of the shirt will be engaged between the flexible strip 14 and the body member 10, this providing ample space for 100 taking care of the lower end of the shirt without rumpling or wrinkling it in a manner which will be evident in case of the removal of the vest. When it is desired to 105 drop down or lower the trousers, it is apparent that when they are unbuttoned at the front they may be pulled away from the body of the wearer at the sides which will allow the body member 10 to straighten 110 out so that the trousers may be lowered the desired extent without necessitating disen-

gagement of the tabs 12 from the button B or disengagement of the strip 14 from the suspenders. When the trousers are subsequently pulled up to their proper position, it is apparent that the body members 10 will fold into their downwardly extending position so that the lower edge of the shirt will be properly disposed between the body members 10 and the strips 14.

10 From the foregoing description and a study of the drawings, it will be apparent that I have thus provided a simply constructed and consequently inexpensive supporter for use in connection with trousers which permit the suspenders to be worn underneath the top or dress shirt while at the same time there will be no disorderly appearance or unsightliness at the lower end of the shirt owing to the fact that the lower 20 end of the shirt is received within a portion of the supporter. Owing to the simplicity of the construction and the fewness of the parts it is apparent that there is nothing at all to get out of order and that the device will consequently have a long life and that it will satisfactorily perform all functions for which it is intended.

While I have shown and described the preferred embodiment of the invention, it is 30 of course to be understood that I reserve the right to make such changes in the form, construction and arrangement of parts as will not depart from the spirit of invention or the scope of the subjoined claims.

35 Having thus described the invention, I claim:

1. A trousers supporter comprising the combination with buttons located on the waist band of trousers and suspenders, of 40 an elongated body member located at each side of the waist band of the trousers, elongated tabs formed on the upper corners of the

body and provided with buttonholes engageable about said buttons, and an elongated flexible strip carried by the lower end 45 of the body and designed to be engaged with the suspenders.

2. A trousers supporter comprising the combination with buttons located on the waist band of trousers and suspenders, of an 50 elongated flexible body member located at each side of the waist band of the trousers, elongated tabs formed on the upper corners of the body and provided with buttonholes engageable about said buttons, and an elongated flexible strip carried by the lower end 55 of the body and designed to be engaged with the suspenders, said strip being looped through the suspenders and being provided with a snap fastener, the strip being furthermore provided with a series of fastener elements adapted to be selectively engaged with said first named snap fastener whereby to maintain adjustment.

3. A trouser supporter comprising a transversely curved elongated body member of somewhat flexible material designed to be disposed against the inside of trousers at the hip line thereof, the body member being of elongated trapezoidal shape and formed 70 at its upper corners with extensions, flexible tabs secured upon said extensions and formed with buttonholes designed to be engaged upon the buttons at the waist band of the trousers, and an elongated flexible 75 strip connected with the lower end of the body and designed to be looped and adjustably secured with respect to the suspenders, the space between the body and the flexible strip being designed to accommodate the 80 lower end of the shirt.

In testimony whereof I affix my signature.

MORGAN A. GREENE.
